UNITED STATES PATENT OFFICE

PASCAL J. SHAMPAY, OF CHICAGO, ILLINOIS

CARPET-CLEANING MACHINE

Application filed October 21, 1922. Serial No. 595,951.

My improvement relates to machines for cleaning carpets, and the like, and has for one of its objects the provision of simple and efficient means for quickly and efficiently cleaning carpets, rugs, and the like.

5 A further object is the provision of a machine of this character adapted to rinse out dust from a carpet, or the like, before the actual scrubbing and cleaning has been begun.

10 A further object is the provision of a machine of this character having elongated brushes which operate reciprocally across a carpet, or the like, to be cleaned.

15 A further object is the provision of efficient means for holding a carpet while being acted upon by brushes.

20 A further object is the provision of means for wetting a carpet and preliminarily scrubbing the carpet under water before the actual cleansing has been begun.

25 A still further object is the provision of means for scrubbing a carpet in one direction across the nap in clear water preliminarily before scrubbing the carpet in a different direction across the nap during the application of soap or other cleansing means with water.

Other objects will appear hereinafter.

30 An embodiment of my invention is illustrated in the accompanying drawings forming a part of this specification and in which—

Fig. 1 is a side elevation of the part of my improved machine for preliminarily wetting a carpet, or the like, and freeing dust therefrom;

35 Fig. 2 is a fragmental plan view of the same;

Fig. 3 is a section taken on line 3—3 of Fig. 2; and Fig. 4 is a view of the feeding end of said device;

40 Fig. 5 is a plan view of the scrubbing and cleaning part of my improved device;

Fig. 6 is a side elevation of the device shown in Fig. 5;

45 Fig. 7 is a longitudinal section of the same; and

Fig. 8 is a fragmental section taken on line 8—8 of Fig. 7.

50 I find that by immersing a carpet, or the like, in water and preliminarily agitating the surface of said carpet the loose dust will

be taken from the carpet and that such carpet will be more easily cleaned by the regular cleaning mechanism than where it is attempted to free the carpet of the loose dust by beating or by dry suction. A device 55 adapted to accomplish the above result is shown in the accompanying drawings, in which a frame 10 of somewhat rectangular construction is indicated. It will be apparent that the frame may be formed of any desired material and of a size and shape to support the parts to be carried thereby. In the present construction I have formed the frame 10 so as to have angular guides 11 at its corners, two of said guides being shown in Fig. 60 2. These guides 11 provide the corner posts of the frame 10. Between said guides 11 I mount a tank 12 which is of a size to extend under the working parts mounted on the frame 10. The tank is adapted to be moved 70 vertically so that when it is desired to clean or inspect such tank, the latter can be lowered to the bottom of frame 10 for easy cleaning or inspecting. As a means for mounting the tank I provide bands 13 at its ends which 75 extend up to the top of the tank and at the top of said bands are connected the ends of cables 14, one cable 14 at each side of the machine. The cables 14 each pass over two pulleys 15 mounted in the frame 10 and are 80 wound around a drum 16 intermediate the ends of the frame. The two drums, one of which is shown, are mounted on a shaft 17 which extends across the frame 10. One end of shaft 17 is provided with a crank 18 for 85 manually rotating the drums 16 to raise and lower the tank 12. When the tank has been raised to its operative or upper position dogs 19 are moved under the tank so as to take the strain off of cables 14. These dogs 19 may 90 be mounted and operated in any desirable manner. I have indicated them as being fixed on a shaft 20 at each side of frame 10. Each of the shafts 20 had a lever 21 fixed thereon and the levers 21 connected together 95 by a link 22 so that by operating one of said shafts 20 both of the shafts with their dogs 19 can be moved under the tank 12 for supporting the latter or moved out from under the tank when it is desired to lower the latter. 100

The tank 12 may be provided with a partition 23 so as to provide a compartment 24 for the reception of a roll of carpet to be cleaned. It will be apparent, however, that the carpet may be held in any desirable manner, but the compartment 24 provides a convenient place for holding such carpet in a roll in position for easily feeding into the dusting machine. An edge of the carpet is taken up over the top of partition 23 and inserted between a slide 25 and feed roller 26. The carpet then passes into an endless table or belt 27 which is mounted on rollers or sprockets 28. The members 28 are fixed on shafts 29 and the latter suitably mounted in frame 10, as indicated in Fig. 3.

A stripper plate 30 is positioned adjacent the delivery end of the endless table 27 so as to conduct the carpet away from said table 27. The latter may be provided with a supporting member 31 under its upper run, as indicated in Fig. 3, to hold its upper surface in substantially a horizontal plane.

At the end of stripper plate 30 are two rollers 32 and 33. The roller 32 is fixed on a shaft 34 mounted in bearings in the frame 10. The roller 33 is fixed on a shaft 35 mounted in bearings adapted for movement away from roller 32. Any suitable form of mounting 30 the bearings of shaft 35 may be provided and that indicated is a convenient form in general use in machines of this character.

A roller 36 is positioned adjacent roller 33 and fixed on a shaft 37 mounted in the frame 10 similarly to shaft 34. The arrangement of roller 33 and its mounting is such that the roller 33 moves away from rollers 32 and 36 at the same time. Around the rollers 32 and 36 are a number of endless 40 cords 38, or the like, which serve to hold the carpet against roller 33 and guide such carpet between rollers 32 and 36.

Above roller 36 is a roller 39 fixed on a shaft 40 which is journaled in the frame 10 similarly to shaft 35 so that the roller 39 can yield away and toward roller 36. The cords 38 may also pass around a small roller 41 suitably mounted in frame 10 so as to hold the carpet up against roller 39 and raise the carpet up over the edge of tank 12.

A water supply pipe 42 is arranged so as to discharge water into tank 12 and preferably between certain of the rollers between which the carpet is passed. I have found that said pipe 42 works advantageously by being positioned between rollers 39 and 33, as indicated in Fig. 3. The tank 12 is also provided with an overflow pipe 43 which may be of flexible material so as to permit the vertical movement of tank 12, as already described. The overflow pipe 43 is preferably at a height so that the water will be maintained in tank 12 above the top of table 27 so as to immerse a carpet while being passed over said table. As soon as the carpet leaves

the stripper 30 rollers 32 and 33 squeeze out the water and such water will again engage the carpet between rollers 36 and 32. The carpet is then squeezed again between rollers 33 and 36 and again comes into contact with the clean water issuing from pipe 42 where it is rinsed, and then such carpet is passed between rollers 36 and 39 for wringing the same. The rollers 41 and 39 further tend to wring the carpet again.

While the carpet is on table 27 I preferably agitate the upper or nap side of such carpet so as to free dust and larger particles of foreign material in said carpet. A set of brushes moved back and forth on the carpet under the water serves as an efficient means for dislodging such dust and other particles. I have indicated four brushes 44 which are considerably longer than their width and mounted across the frame trans-

versely of the path of the carpet through the machine. These brushes may be mounted and operated in any approved manner. I have indicated guides 45 extending through the portions of the frame 10 which support the carpet guide rollers, the bars being supported by these portions of the frame. Upon the guides 45 are a plurality of members 46 which are secured to the tops of the brushes 44 in any approved manner, such as by the screws 95 indicated. As a reinforcement for the brushes I have indicated a longitudinally extending bar 47 above each of said brushes and its corresponding guide. These bars 47 are secured to the members 46 as clearly indicated. To each of the bars 47 is secured an upstanding ear 48 and each of the ears 48 is connected by means of a link 49 to a crank shaft 50. The crank shaft, of course, has a separate crank for each of the links 49. The crank shaft 50 is mounted in suitable bearings and connected by means of sprocket gearing 51 to a shaft 52 which in turn is connected by suitable gearing in a housing 53 with a motor 54. The shaft 52 110 may also be connected through suitable gearing in housing 55 with the shafts 34, 35, 37 and 40 so as to operate the rollers on said shafts. It will be apparent that the surface speeds of rollers 32, 33, 36 and 39 are substantially the same as the surface speed of table 27.

On rollers 33 and 39 I preferably provide wrappings of rope 56 so that while the carpet is squeezed in passing through the rollers as aforementioned, there are still pockets in the rollers 33 and 39 permitting a quantity of water to run along on the top of the carpet.

The foregoing parts are those for rinsing out loose dust and other particles of foreign material from the carpet before the actual cleaning and scrubbing has been begun. Heretofore the dusting has been done by beating and by suction means, and one of the important features of this invention is to pre-

liminarily remove dust from carpets by rinsing such carpet before actually scrubbing the same.

I have indicated a frame 60 of suitable size and shape to support the scrubbing apparatus. The form shown simply indicates a means for holding these parts and may be varied as desired. In Figs. 1 to 4, inclusive, this part of the mechanism is considered as being viewed from one side, and in Figs. 5, 6, 7 and 8 the rest of the machine is being viewed as from the opposite side of the machine. After the carpet leaves the mechanism in frame 10 and passes from roller 41 it is passed into a trough 61 in frame 60 where a quantity of liquid soap is introduced through a feed pipe 62. The soap may be maintained in trough 61 at any desirable height. Disposed in the trough 61 is a roller 63 which is preferably of a foraminous substance, such as woven wire, so as to permit the liquid soap to pass freely into the roller and around the same. A carpet upon passing through the trough is passed under the roller 63 so that the soap inside of the roller can engage one side of the carpet and that under the roller engage the other side of the carpet. In this manner the soap is applied to both sides of the carpet and readily adheres to the carpet since the latter is wet from the apparatus in frame 10. The roller 63 may be mounted in any desirable manner, such as being fixed on a shaft 64 mounted in frame 60.

In the frame 60 is mounted a tank 65 which has one end adjacent trough 61 and is adapted to contain water and the other scrubbing agents used in cleaning a carpet. The tank 65 may have any desired form and may be mounted as indicated in Fig. 7 so that it cannot be moved in frame 60, or, it may be mounted similarly to tank 12 in frame 10, as already described. Said tank 65 preferably has the end adjacent trough 61 lower than the other end so as to insure that the water and liquid soap or other cleaning agents will drain back toward said trough 61.

In tank 65 adjacent trough 61 is a brush 66 fixed on a shaft 67 mounted in suitable bearings in frame 60. Above the brush 66 is a roller 68 having short bristles 69 thereon and spaced points 70. The bristles provide a firm backing for holding the carpet against brush 66 during scrubbing of the bottom of the carpet. The points 70 engage the top of the carpet and both feed the carpet along and prevent such carpet from being moved too fast by brush 66. The carpet after leaving brush 66 and roller 68 is directed onto an endless table 71 which is mounted on rollers or sprockets 72 fixed on shafts 73 and the latter mounted in suitable bearings in frame 60. The upper run of the table 71 may be provided with a support 74 for holding the top surface of such table in a substantially horizontal plane.

The table 71 preferably has a plurality of points 75 in its outer surface so as to engage the carpet passing over such table and holding the latter against movement on the table by the cleaning elements to be described later. A resilient member 75' may be provided so as to press the carpet down onto point 75, as clearly indicated in Fig. 7. Above the table 71 I provide a plurality of elongated brushes 76. In the form shown there are two sets of the brushes 76 and such brushes disposed longitudinally of the path of the carpet through the machine. It will be apparent that a fewer or greater number of sets of these brushes may be provided.

The brushes 76 may be mounted for reciprocatory movements in any desirable manner. I have indicated each of the brushes 76 having a link 77 adjacent each end and pivoted to downwardly extending ears 78 on a head 79. Also pivoted to the tops of the ends of brushes 76 are rods 80 which extend upwardly through the heads 79, as clearly indicated in Fig. 7. Between the heads 79 and the pivotal connections of the rods 80 with the brushes 76 are compression springs 81 which tend to press downwardly on the brushes forcing the latter toward the table 71. Each of the rods 80 is provided with a nut 82 threaded thereon for limiting the movement of said brushes toward the table 71. In use the nuts are preferably arranged so that the brushes cannot quite touch the table 71 but can engage the carpet and apply sufficient force thereto to effect efficient scrubbing of the carpet.

The heads in each set of brushes 76 are divided into sets with one set of alternate heads secured to a bar 83 extending across the frame. Said bars 83 are mounted on guides 84 which extend longitudinally of the path of the carpet through the machine so the brushes 76 may reciprocate back and forth on the upper surface of the carpet in use. Midway between each set of brushes 76 in the form indicated are provided two levers 85 with their pivotal points 86 at points near the guides 84, as clearly indicated in Fig. 6. The upper ends of levers 85 are connected by links 87 to the mountings of two of the bars 83. The lower portions of said levers 85 are connected by means of links 88 to the other two bars 83 so that alternate bars 83 move in one direction, while the other two alternate bars 83 are moved in the other direction. This causes alternate brushes in each set to move in one direction, while the other alternate brushes in such set move in the other direction. The lower ends of levers 85 are connected by means of links 88 with crank pins 89 on shaft 67. It will be apparent that the brushes 76 and 66 should be moved at greater speeds than the speed of the carpet through the machine while rollers 63, 68, and table 71 are moved at substantially the speed of the

carpet through the machine. Any suitable form of gearing may be provided to rotate shafts 64, 67, 68 and 73, such as the sprocket and chain connection indicated in Fig. 6, or any suitable driving mechanism may be provided. The shaft 67 is indicated as being connected to shaft 73 by a sprocket and chain gearing with a difference of speed indicated and it will be apparent that shaft 67 should be rotated as much faster than shaft 73 as necessary to accomplish the desired speeds of brushes 66 and 76 to effectively scrub the carpet.

Between the brushes 76 I provide thin plates 90 which are adapted to hold the carpet down on table 71 and facilitate holding the carpet against the action of brushes 76. These plates 90 may be mounted in any desirable manner, such as by providing up-standing rods 91 which pass through bars 92 extending across the frame. Around each rod 91 is a spring 93 which tends to force its plate downwardly toward the table 71. A nut 94 is provided on each of the rods 91 to limit the downward movement of the plates 90 so that the latter exert sufficient pressure on the carpet and be held away from table 71 when there is no carpet in the machine.

At an end of tank 65 is provided a rinsing tank 95 and a pair of wringing rollers 96 provided to wring the carpet as it passes from the machine. Before the carpet is wrung by rollers 96 water supply pipes 97 are adapted to discharge water against the upper and lower sides of the carpet as clearly indicated in Fig. 7. As soon as the water rinses off the soapy water used in the scrubbing, the carpet is wrung by rollers 96 and is then ready to be dried. The rollers 96 are indicated as fixed on shafts 98 which are mounted in suitable bearings in frame 60. The shafts 98 are connected together by gears 99 and one of said gears 98 is connected by a belt or other gearing 100 with one of shafts 73, see Fig. 6.

I preferably provide thin wires 101 which extend across the tops of tank 65 so as to conduct carpets through the machine and strip such carpets off of table 71 and insure the passage of such carpets through the machine. One end of each of the wires is connected as at 102 in the machine, and the other end secured as at 103.

In Fig. 5 it will be apparent that the brushes 76 at one side of the levers 85 are offset or staggered with relation to the brushes at the other side of said levers so that one set of brushes will scrub any spaces left between the brushes of the other set. Also, the plates 90 are staggered so as to be disposed between the brushes as just described.

I claim:—

1. A carpet cleaning machine comprising an endless table adapted for movement in one direction, and a plurality of brushes mounted above the table for straight line

reciprocatory movements in the direction of the movement of the carpet.

2. A carpet cleaning machine comprising an endless conveyer table adapted for movement in one direction, a plurality of brushes mounted for back and forth movements, and means for spacing said brushes slightly from said table.

3. A carpet cleaning machine comprising guides, heads on said guides, brushes mounted on said heads, the brushes on one head being disposed out of registration with the brushes on the next adjacent head to break joint with the brushes of the adjacent head, means for moving some of said heads in one direction and the rest of said heads in the opposite direction at the same time, and means for moving a carpet across the brushes.

4. A carpet cleaning machine comprising a plurality of elongated brushes mounted for reciprocatory movements, means for moving a carpet across the brushes, and means extending between the brushes in the direction of the movement of the carpet for holding the carpet against the carpet-moving means.

5. A carpet cleaning machine comprising an endless conveyer table adapted for movement in one direction, elongated brushes resiliently mounted above the table, thin blades resiliently mounted between the brushes, means for moving the brushes back and forth over the table, and means for moving a carpet between said brushes and table.

6. A carpet cleaning machine comprising guides, heads on said guides, brushes under said heads, links connecting the brushes with said heads, and means for moving the heads to move the brushes longitudinally of the latter.

7. A carpet cleaning machine comprising guides, heads on said guides and having openings therethrough, brushes under said heads, links connecting the brushes with said heads, rods attached to the heads and engaging said openings, springs around said rods and between the brushes and heads, and nuts threaded on the rods above the heads.

8. A carpet cleaning machine comprising guides, heads on said guides, brushes under said heads, links connecting the brushes with said heads, compression springs between the heads and brushes, a table having its upper surface adjacent said brushes and means for moving the heads to move the brushes back and forth over said table.

9. A carpet cleaning machine comprising a frame, guides at opposite sides of the frame, two heads extending across the frame and mounted on said guides, elongated brushes side by side across the frame, means securing one set of alternate brushes

to one of the heads, means securing the other set of alternate brushes to the other head, means for moving one of the heads in one direction and the other head in the opposite direction at the same time, and means for moving a carpet between the brushes and table.

10. A carpet cleaning machine comprising a frame, a soap trough in said frame extending laterally across the latter, a foraminous drum mounted in the soap trough, a brush adjacent the soap trough in said frame, and means for holding a carpet against said brush.

15. A carpet cleaning machine comprising a frame, a cylindrical scrubbing brush, a cylindrical brush above the scrubbing brush, and points in the second-mentioned brush extending beyond the bristles of the latter toward said scrubbing brush.

20. A carpet cleaning machine comprising a frame, a soap trough in said frame, a foraminous drum in said trough spaced from the latter providing a carpet path between said drum and trough, a scrubbing brush having its top part substantially level with the top edges of said trough, a brush above said scrubbing brush adapted to hold a carpet against the latter, and points in said second-mentioned brush adapted to engage a carpet and hold the latter against the influence of said scrubbing brush and said drum.

25. A carpet cleaning machine comprising a frame, soaping mechanism at one end of said frame, a tank in said frame having its bottom wall inclined and the lowest part of the wall adjacent said soaping mechanism, agitating means in said tank adjacent the lowest portion of the bottom of the tank, scrubbing mechanism above the tank and means for moving a carpet from said agitating means to said scrubbing mechanism.

30. A carpet cleaning machine comprising an endless table, a plurality of spaced plates standing edgewise to and above said table, brushes between said plates adapted for movement longitudinally of the plates over said table, and means for feeding soap and other cleaning agents to the top of a carpet, and means for rinsing a carpet after the latter has left said brushes and table.

35. A carpet cleaning machine comprising an endless table mounted for movement in one direction, a plurality of spaced plates mounted edgewise to and spaced slightly above said table, means for varying the height of said plates from said table, elongated brushes mounted between said plates and adapted for reciprocating movements and means for adjusting said brushes to various heights above said table.

40. A scrubbing machine comprising a table; carpet-engaging points on said table;

a plurality of brushes mounted for reciprocating movements above said table; and plates disposed between said brushes and adapted to cooperate with the points for holding a carpet on the table against the influence of said brushes.

45. A scrubbing machine comprising a table; upstanding carpet-engaging points on said table; elongated offset brushes mounted for reciprocating movements above said table; and plates disposed between said brushes with their edges adjacent said table, the brushes and points being adapted to facilitate holding the carpet against the influence of the reciprocating brushes.

50. Carpet scrubbing mechanism comprising a table; a plurality of offset elongated brushes reciprocally mounted over said table; and a plurality of plates between said brushes with their edges adjacent said table and adapted to facilitate holding a carpet on the table against the influence of said brushes.

55. Carpet scrubbing mechanism comprising an endless table having carpet-engaging points extending from its surface; and a plurality of offset brushes disposed above said table, the points on said table being adapted to facilitate holding the carpet against the influence of said reciprocating brushes.

60. A carpet cleaning machine comprising an endless table; and a plurality of elongated reciprocating brushes disposed above the table with certain of the brushes offset with respect to the other brushes and all of such brushes being adapted to engage a carpet on said table.

65. Carpet scrubbing mechanism comprising an endless table; points extending outwardly from said table; and a plurality of elongated brushes reciprocally mounted above the table and also having means providing resilient movements away from and toward the table, such brushes being divided into two sets with one set of brushes offset with respect to the other set.

70. In testimony whereof I have signed my name to this specification on this 19th day of October A. D. 1922.

PASCAL J. SHAMPAY.
